UNITED STATES PATENT OFFICE.

GEORGE HERBERT BENNETT, OF SEDBERGH, ENGLAND.

HERMETIC CLOSURE FOR CANS, BOXES, JARS, BOTTLES, AND THE LIKE CONTAINERS.

Application filed November 23, 1925, Serial No. 70,825, and in Great Britain December 15, 1924.

This invention relates to improvements in hermetic closures for cans or boxes of sheet metal, also bottles, jars or other like containers, and has for its object to hermetically seal in containers under a vacuum substances which are liable to deteriorate by exposure to the atmosphere, or which require to be protected against climatic changes or the attacks of insects. The improved closures are particularly applicable for packing tobacco, cigarettes, sterile foods, delicacies and preserves.

According to my invention a ring or band of rubber or other suitable elastic material, and of less diameter than the container is stretched around the mouth or lip of the container (or in the case of a cover or closure member of plug type on the spigot part thereof) and is compressed when the cover is applied and the closure effected, between rims or flanges provided on the body and cover of the container.

In one mode of carrying out the invention a hermetic closure is obtained by a thin ring or band of rubber or other suitable elastic material and of less diameter than the joint to be made being stretched and placed vertically over and around the mouth of the container (or, in the case of a cover or closure member of plug type, on the spigot part thereof), so that when the closure member is pressed down, the rubber ring is squeezed between the container and a flange on the closure-member, and caused to bulge outwards from its middle to form a channel shaped packing. The section of the rubber or other elastic ring or band used must of course be such that it can be doubled and compressed into channel form as described.

I may provide a groove around the lip or mouth of the container, or in the case of a plug cap or stopper for closing a bottle or jar or a lever lid tin the said groove is formed on the spigot part of the cap or stopper. When the thin rubber or other elastic ring or band is placed in position, one edge of it takes more or less into the annular groove, and the bending of the ring in an outward direction at its middle is thus started. Further, that part of the container body (or its plug cap or stopper) on which the ring or band is stretched is made somewhat rounded or convex in curvature in a vertical plane so that the ring or band is caused to assume a slightly curved form. By these means the doubling of the thin packing ring into chan-

nel section when the lid or cover is pressed down therein is facilitated.

The thickness of the stretched rubber is such that the rubber can be easily perforated by a sharp instrument when it is desired to break the vacuum and open the container. To facilitate the opening of the vacuumized containers, and to avoid having to pierce the rubber by a sharp instrument when opening, I may provide the rubber ring with a metal or other tag. When it is desired to open the container, the tag is pulled, so as to stretch the ring and thus break the vacuum by admitting air. The lid or closure-member can then be easily removed.

In another form of the closure intended for cans or boxes with a cover or lid having a skirt fitting over the open top or mouth of the container, but applicable also to cans or tins of the lever-lid type, I use a ring of rubber or rubber substitute which is not compressed into channel form when the closure is effected. In this arrangement the hermetic closure is obtained by means of a ring of rubber or rubber substitute of less diameter than the joint to be made and of circular, square or like section, which is stretched over the mouth of the container with its inner side seated in a shallow groove and is compressed when the closure is effected between rims or flanges on the body and cover of the container. Under the downward pressure of the lid or cover, caused by the air pressure on it, the ring is pressed downwards and inwards on its seat. Preferably the cover has a simple horizontal flange, and at the angle between the horizontal flange and the skirt of the cover is flattened or provided with an inclined surface to give a wedging effect on the rubber ring and direct pressure inward to gain a maximum surface contact on the rubber.

In order to render the joint produced by my improved closures mechanically secure, any suitable locking means may be provided. These means may, for example, take the form of clips or a band of channel section fitted on the rims or flanges of the container and its cover. In another form, where a simple flange is used on the cover, the peripheral edge of the said flange is provided at several points with integral lugs or tongues which, when the container is closed, may be bent over and compressed by a suitable tool so as to firmly embrace the flange on the container body.

The invention will be further described with reference to the accompanying drawings, in which:

Figure 1 is an elevation, partly in section, of a sheet metal box hermetically closed in accordance with my invention and provided with a protecting band;

Figure 2 is a similar view of portion of a jar or bottle;

Figure 3 is an elevation, partly in section, of another sheet metal box, with its lid separate. This view illustrates the use of an annular groove around the lip of the box, and also shows the position of the packing ring or band before the lid is put on.

Figure 4 is an elevation, partly in section, of a portion of a jar or bottle and its closure-member, illustrating on the left how the packing ring may be preliminarily doubled on itself before the closure-member is put on.

Figure 5 illustrates a closure-member with a simple flange.

Figures 6 and 7 show the invention applied to jars or bottles with a plug-cap or stopper.

Figure 8 shows the invention applied to a lever-lid can.

Figure 9 is an elevation, partly in section, of a sheet metal box or can illustrating an arrangement in which the jointing member is a solid ring.

Figure 10 is a plan view of a detail.

Figures 11 to 14 illustrate means for opening the hermetic closure by a tag applied to the channel shaped joint ring.

Figures 11 and 12 are respectively an elevation and plan of the tag itself;

Figure 13 is an elevation of part of a tin box, showing the rubber joint ring with the tag in the position before the lid is pressed down;

Figure 14 shows the position when the lid is fully pressed down.

Referring first, more particularly, to Fig. 1, which shows the invention as applied to a can or box of sheet metal, the body 1 and lid or cover 2 (which may, of course, be of any convenient shape and size) may be solid drawn and thereby seamless, or made with soldered seams or otherwise made airtight, and with the cover similarly constructed or as is more usual, solid drawn.

Around the extreme edge of the lid or cover and also a short distance below the lip on the body of the box, flat rims or flanges, 3 and 4 respectively, are produced by suitable dies. These rims or flanges may be formed by pressing out a bead in the sheet material and then flattening the bead between suitable dies to provide a substantially horizontal effective surface. The lid or cover is made to fit snugly on to the body, the two rims or flanges meeting flush.

It will be understood that where in the

course of this specification and its claims reference is made to "horizontal", by this is intended a plane at right angles to the axis of a round box: since this is the usual position of the member denominated horizontal during the operation of closing and sealing the container. Furthermore, such flanges or rims may generally be referred to as ribs, and more specifically when the container is of sheet metal, as beads. Such a bead is preferably formed in the practice of the invention by forming an open bead in the wall of the container or the cover member, which projects outwardly from the wall, and thereafter flattening the bead so formed between suitable dies so that it is given the form shown in the several figures.

In order to obtain a hermetic closure, a thin ring or band 5, of rubber or rubber substitute, about half the diameter of the joint to be made, is stretched and placed vertically over the mouth of the container, and rests evenly on the rim or flange 3. The lid being pressed on, the rubber ring is squeezed between the two rims or flanges 3 and 4, forcing it to bulge outwards from the middle to a channel section, as shown in Fig. 1. Due to the tension on the ring, it constantly tends to open out, thus creating a large amount of spring or "cushion" and the harder it is pressed down the more surface it covers. The packing ring may be an ordinary rubber band, flat in horizontal section, which is stretched vertically around the mouth of the container (or in some cases the cap or stopper) or it may be a thin rubber ring of cylindrical and tubular form. In any case, the depth of the ring or band, when placed vertically on the container, is such e. g. as shown in Fig. 3, that when doubled and compressed by the closing down of the closure-member, the ring or band forms a channel-shaped packing of the desired width, which is preferably equal to the width of the rims or flanges between which it is compressed.

Such a rubber joint-ring is designed to give the maximum amount of "cushion" with the use of a minimum amount of rubber. In my experiments I have successfully used an ordinary thin flat rubber band or ring, and it is probably the cheapest form of rubber ring obtainable. In order to get the amount of "cushion" and contact surface necessary to resist vacuum pressure, rubber rings of heavy square or round section have hitherto been used for glass jars. By my invention, however, a sound joint is made with a rubber ring costing only a fraction of those in general use.

It will be understood that in effecting a hermetic closure according to my invention after the container is filled, the cover is slipped on and held in place by a spring clamp or a weight. On heating the con-

tainer, air is forced out, and the clamp furnishes sufficient pressure to prevent the air rushing back. As the container cools, a partial vacuum is formed, and the lid is held 5 permanently secure. When the contents are susceptible to damage by excessive heat, or again if a full vacuum (95%) is desired, the air is extracted by mechanical means, and otherwise the closure is effected in exactly 10 the same manner as described.

To render the joint also mechanically secure, a protecting band 6 of channel shape is secured around the flanges 3 and 4 with its ends hooked together, or alternatively, clips 15 might be provided adapted to grip the said flanges and hold them tightly pressed together.

To open the container, the protecting band or clips—if any—is removed, and the rubber jointing ring is so thin that it can be easily pierced with the point of a penknife or other sharp-pointed instrument, allowing air to enter and thus breaking the vacuum, and so loosening the cover that it may be 20 removed without difficulty. As an alternative, to facilitate the opening of the container, and to avoid having to use a knife to pierce the ring, the joint-ring is fitted with a pull-out tag, as hereinafter described 25 with reference to Figures 11 to 14. With the hermetic seal broken, the container remains intact, and having a tightly-fitting lid, it may be used to hold the contents as long as required.

30 The lid or cover may have a simple flange (as in Fig. 5) formed of a single thickness of metal, or I may turn or bend the metal of the flange inwards again, as indicated at 7 in Figs. 1-4, so as to make the flange with 40 a double layer of metal and with a rounded or beaded edge; and this inturned portion 7 on the lower side of the flange extends inwards to such an extent as to produce a flat surface which, when the lid or cover is 45 pressed down, comes against the top edge of the vertically-placed rubber packing ring or band, and prevents the said band or ring entering and wedging between the cover and the lip on the body of the container.

50 Figure 2 shows my hermetic closure applied to a jar or bottle fitted with a metal lid or stopper. In other respects the closure is exactly the same as described with reference to Fig. 1 and the same reference numerals are used in the drawings to indicate the same or similar parts in both figures.

55 Figure 3 illustrates a modification, according to which I provide an annular groove 8 around the lip or mouth of the container 1. When the thin rubber or other elastic ring 5 is placed in position, the lower edge of it takes more or less into the annular groove, and the bending of the ring in an outward 60 direction from its middle is thus started.

Further, to this end, the surface of the lip of the container above the groove 8 on which the ring or band is stretched, although substantially cylindrical may be made somewhat rounded or slightly convexly-curved 70 in a vertical plane, i. e., barrel-shaped as at 9, so that the ring 5 is thereby caused to assume a slightly curved form and is under greater tension at its central than at its end planes. By these means the doubling of the 75 thin packing ring on itself into the channel form when the lid or cover is pressed down is facilitated.

The container and its lid shown in Fig. 3 may be made entirely of metal, or of glass 80 or other suitable material, or part may be of one material and part of the other.

Figure 4 shows a jar or bottle similar to that of Fig. 2 except that in this case an annular groove and rounded lip are provided, as already described in connection with Fig. 3. The jar has a flange or collar 3 on which a protecting ring can be fitted, if desired. A lid or cover with an inturned flange may be used, or a cover with a simple flange, as in Fig. 5. In this latter case, the rubber or other elastic ring 5 can first be pressed down by using a plain ring-shaped tool, whereby the ring 5 is doubled on itself, as shown on the left side of Fig. 4, 90 and is held in position by both its edges engaging in the annular groove 8 around the mouth of the container.

Figure 6 shows a jar or bottle fitted with a plug-cap 2 of sheet metal. In this case, it 100 will be noted, the annular groove 8 is formed in the spigot part of the cap.

The same idea is shown in Fig. 7, but here a screw-cap 10 is provided in place of a protecting band and for sealing the jar or bottle after the vacuum is broken and the container is in use. In all these various modifications, it will be understood that when the closure is effected the rubber or other elastic packing ring is doubled and compressed between 105 the container and a flange on the lid or cover, as already more particularly explained.

Figure 8 shows the invention applied to a lever-lid can, the ring 5 again in this case, when the closure is made, being doubled and compressed in channel section between the flange 4 of the lid or stopper and the rim 3 surrounding the mouth of the can.

Figure 9 illustrates another form of closure for closing sheet-metal cans or boxes under a vacuum. In this arrangement a hermetic closure is obtained by means of a ring 11 of rubber or rubber substitute of less diameter than the joint to be made and of circular, square or like section, which is stretched over the mouth of the container 12 and rests evenly on the rim or flange 13 with its inner side lying in a shallow groove 14. Preferably a ring of circular section and of 120 good quality rubber is used for this type of 130

closure. By the downward pressure of the cover 15 after the container has been closed under a vacuum the ring 11 is strongly pressed downwards and inwards between the flanges 13 and 16. It is to be noted that the cover is shown in Fig. 9 in its position before the container is exhausted, and it is not therefore fully pressed down.

The cover may have a simple flange, as shown in Fig. 9 or an inturned flange of the kind shown in Figs. 1-3. Preferably, the cover is made with a simple flange 16, which at the angle is made with an inclined surface 17 to give a wedging effect on the ring and a direct pressure inward so as to gain a maximum surface contact on the rubber.

The flange 13 on the body of the can is designed to act also as a stiffening ring to prevent distortion around the path of the joint.

The top of the cover 15 is preferably dished.

The joint can be rendered mechanically secure by forming the flange 16 at several points around its periphery with integral tongues or lugs 18, such as indicated in plan view in Fig. 10. When the container is closed these lugs are bent over and compressed by a suitable tool so as to firmly embrace the flange 13 on the body of the container, as indicated in dotted lines in Fig. 9.

In the case of a lever lid can, the jointing ring is stretched on the spigot part of the lid with its inner side bearing in a shallow groove and is compressed between the flange of the lid and a rim surrounding the mouth of the can.

To facilitate the opening of vacuumized containers closed with a packing-ring bent and compressed into channel form as hereinbefore described, I provide the ring or band, whether of the collar or flat pattern, with a metal or other tag having a shank which is inserted through a perforation in the ring or band and a head portion adapted to lie in the folds of the ring. The preferred construction and application of this tag will be readily understood from the following description and with reference to Figs. 11-14. The tag 19, which is shown by itself in Figs. 11 and 12, consists of a very thin T-shaped strip of metal or other suitable material having one end bent down, as at 20, and the other end 21 pointed and preferably corrugated to form a gripping surface for the fingers. Just below its head end 20 the tag is formed with a notch or slot 22 at each side. The tag 19 is fitted to the rubber jointing ring 5 by first stretching the ring to about three times its relaxed size over a frame. A small hole is then pierced with a needle at one point through the ring, so as to make an easy entry for the point of the tag, which is then pressed through to the shoulder slots 22. On the ring being relaxed, the rubber contracts

into these slots 22 and closes tightly around the tag. The tagged ring 5 being half the diameter of the container, when it is stretched into place on the lip of the container, the rubber around the hole is still partly relaxed, and therefore continues to fit tightly around the tag. Fig. 13 shows the position of the ring and tag before the lid 2 is pressed down. When the lid is fully pressed down the head end 20 of the tag is gripped between the folds of the rubber ring, and the tag assumes the position shown in Fig. 14.

With this arrangement, when it is desired to open the container, the tag is pulled, so as to stretch the ring and thus break the vacuum by admitting air. The lid of the container can then be easily pulled off.

I declare that what I claim is:

1. Means for hermetically closing exhaust ed containers of the kind specified having an internal member provided with an outwardly extending flange and an external member adapted to fit about said internal member and presenting a surface substantially parallel to and adapted to be brought against said flange, an annular jointing member of elastic material with its outer periphery of lesser normal diameter than said internal member and stretched about the same, said external member permitting during its seating a compression of the stretched jointing member between its said surface and the flange of said internal member.

2. The method of establishing a seal between an internal member having a projecting flange and an external member having an end surface corresponding to said flange, by means of an elastic sealing member with its outer periphery of lesser diameter than said internal member, which consists in stretching said elastic member and placing it over said internal member, and thereafter compressing said stretched elastic member between said surface and said flange while permitting it to yield outwardly to establish a further tension upon its portion contacting said internal member.

3. The method of establishing a seal between the body and cover of a hermetically closed container, by means of an elastic annular sealing member which consists in stretching said member to increase its periphery, and thereafter compressing said stretched member parallel to its axis.

4. Means for hermetically closing containers having a projecting flange adjacent the end to be closed, comprising a sealing member of elastic material of greater dimension in the direction of its axis than in its own plane, said sealing member having its outer periphery of lesser normal diameter than the end of said container to be sealed, and stretched therearound, and means to com-

- press the stretched ring in the direction of its axis, whereby said sealing member is held tightly against the end flange of said container.
5. Means for hermetically closing exhausted containers of the kind specified, said containers having a horizontal outstanding external flange on the body below the mouth, comprising a lid or cover having a depending flange or skirt adapted to fit over the open top or mouth of the container and having a horizontally outstanding flange at its lower edge, and a jointed ring of elastic and compressible material which is placed 10 with all its parts under tension around the container and is compressed between the said horizontal flanges of the container and on the lid or cover to produce a hermetic closure when the lid or cover is closed down 15 under a vacuum.
6. Means for hermetically closing exhausted containers of the kind specified, said containers having horizontally outstanding external flanges on its body below its mouth, and an external groove around the container immediately above said outstanding flange, comprising a lid or cover having a depending skirt or flange adapted to fit over the open top or mouth of the container and having 20 a horizontally outstanding flange at its lower edge, said container being convexly and inwardly curved above said groove to its upper edge, and a jointing ring of elastic and compressible material which is placed 25 under tension around the container in said groove and upon said curved portion, and is compressed flat between the said horizontal flanges to produce a hermetic closure when the lid or cover is closed down under a vacuum.
7. Means for hermetically closing exhausted containers of the kind specified, comprising an annular jointing-ring of elastic material and of less diameter than the container, which jointing-member is stretched 30 in a vertical position around the part where the joint is to be made and is of such form as to be adapted when the said cover is pressed down to be bent and compressed between flanges on the container and the cover to form a channel shaped packing.
8. Means for hermetically closing exhausted containers of the kind specified, comprising an annular jointing-ring consisting of a thin rubber ring, flat in horizontal section and of less diameter than the container, which is stretched in a vertical position around the mouth of the container; a groove in which a portion of said jointing-ring seats itself; and horizontal flanges on the said container and its cover or closure-member, between which the said ring is bent and compressed to form a channel shaped packing when the closure-member is pressed down.
9. Means for hermetically closing exhausted containers of the kind specified, comprising an annular jointing-member consisting of a thin rubber ring, flat in horizontal section and of less diameter than the container, which is placed in a vertical position on the container at the part where the joint is to be made; a surface convexly curved on which said jointing-ring is placed; a groove in which a portion of said jointing-ring seats itself; and horizontal flanges on the body of the container and its closure-member between which the jointing ring is compressed to form a channel shaped packing.
10. In a hermetically closable container of the kind specified, a container body and a closure member for the same, one of said members presenting a plug to enter a cavity of the other member, said members presenting cooperating flanges, an annular jointing ring of elastic material and having its outer periphery of less diameter than the plug, said jointing ring being tightly stretched around said plug adjacent its respective flange and being of such form as to be compressed and deformed between said flanges when said cover member is pressed down upon said body member, whereby to form a channel-shaped packing between said flanges upon said plug.
11. A hermetically sealed sheet metal can and cover, said can having an outstanding external bead with a horizontal top surface, said can having a portion extending upwardly from said horizontal surface; said cover having a depending skirt adapted to fit closely over said upwardly extending portion, and presenting an outstanding flange having a horizontal bottom surface opposite said can bead; and a jointing ring of compressible and elastic material located on said upwardly extending can portion between said flanges, said ring being forced along said upwardly extending portion of the can by the cover flange, and compressed as a whole between the horizontal surfaces thereof to produce a hermetic closure when the cover is closed down under a vacuum.
12. A hermetically sealed container comprising a body member; a cover member and a jointing ring; one of said members having an outstanding external flange with a horizontal surface, said member also having a barrel-shaped portion extending away from said horizontal surface; said other member having a skirt adapted to fit closely over said barrel-shaped portion and presenting an outstanding flange having a horizontal surface opposite said first horizontal surface; said jointing ring being of compressible and elastic material located on said barrel-shaped portion between said flanges and compressed between the horizontal surfaces thereof in a channel shape to produce a hermetic closure when the cover is closed down under a vacuum, said ring being of

lesser diameter than said portion when free and being stretched over said portion during assembly whereby said ring is stretched more at the center plane of said portion than at the end planes so that during compression the edges of the ring are caused to move along said portion while the central portion is caused to move away therefrom.

13. The method of establishing a seal between an internal member having an outstanding flange and an external member having a surface corresponding and parallel to said flange, by means of a thin wide elastic sealing member of lesser diameter than said internal member, which comprises stretching said sealing member and placing it over said internal member, maintaining said sealing member of greater diameter at its center plane than at its end planes, and compressing said sealing member between said surface and flange so that the ends of said sealing member are brought together to form said sealing member into a channel-shaped ring.

14. In a hermetically closable container of the kind specified, a container member and a closure member for the same, one of said members presenting a plug to enter a cavity of the other member, said first member having an outwardly extending horizontal flange, said other member having a flat horizontal flange thereon produced by form-

ing a bead and then flattening it between dies; and a jointing ring of compressible and elastic material located on said plug and compressed between said flanges to produce a hermetic closure when said members are closed together under a vacuum.

15. The method of making a sheet metal container member having a flat horizontal flange adjacent its open end and adapted to compress a sealing ring, which comprises forming a bead in the wall of the member, and thereafter flattening said bead between dies.

16. The method of sealing a hermetically closed container member and a cover member for the same, one of said members fitting inside the other and each having a radially projecting flange, by means of an elastic sealing element, which consists in stretching said elastic element around the inner of said closure members, whereby to increase the periphery of the elastic element and maintain it in position on said member, compressing said stretched element axially between the flanges, and maintaining said element peripherally stretched and axially compressed.

In witness whereof, I have hereunto signed my name this 10th day of November, 1925.

GEORGE HERBERT BENNETT.
